(57) **CLAIM**

The ornamental design for a tray for fill and finish machines as shown and described.

DESCRIPTION

FIG. 1 is a left side top perspective view of a tray for fill and finish machines showing our new design;

FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof;

FIG. 8 is a right side top perspective view thereof;

FIG. 9 is a left side bottom perspective view thereof; and,

FIG. 10 is a right side bottom perspective view thereof.

In the drawings, the broken lines are for the purpose of illustrating portions of the article that form no part of the claimed design. The design does not claim protection for a specific coloring.

1 Claim, 10 Drawing Sheets
